UNITED STATES PATENT OFFICE

THOMAS J. SEXTON, OF HENRYETTA, OKLAHOMA

DRINKING FOUNTAIN

Application filed October 27, 1930. Serial No. 491,542.

My invention relates to improvements in drinking fountains for humans and has for its primary object to provide a novel and improved device of this character which can readily and cheaply be attached to any water system.

Another object is to provide a drinking fountain which is capable of serving a plurality of drinkers at the same time.

Another object is to provide a drinking fountain that can be detached quickly from a water system and stored away when not in use.

A further object of the invention is to provide a drinking fountain peculiarly adapted for use in a community not having a central water supply system and where individual wells supply the community's needs.

Still another object is to provide means whereby the individual fountains operate independently and automatically cut off the water when not in use.

These and other objects and advantages of the invention are obtained by certain novel features of construction, combination and arrangement of parts and can readily be seen and understood by those skilled in the art upon reference to the accompanying description and drawing forming a part of this specification.

In the drawing,

Figure 1 is a side elevation of the invention in its preferred embodiment; and,

Figure 2 is a sectional view on the line 35 2-2 of Figure 1.

In operation, the force pump 2 draws water from a well or other source (not shown) and forces it through the pipe 3, the check valve 4, the pipe 5 and into the tank situated at any point above the fountain. The tank 1 may be of any form or capacity but as herein shown is of cylindrical form and is provided with an overflow pipe 6 and a cover or lid 7. When the tank 1 is filled the pump 2 is stopped and the water is prevented from flowing back to its source by the check valve 4 which may be of any suitable construction.

The pipe 8 is connected by the T-joint 9 to the pipe 5, extending horizontally therefrom and consisting of a number of sections

of pipe 8^a jointed together by T-joints 10 (Figure 2 shows one in section) the end section 8^b being further provided with the stopcock 12 by means of which portable water receptacles may be filled, a hose may be attached or by which the tank 1, may be drained.

The bubble-fountains 11 are connected to the T-joints 10 by the pipe couplings 13 of usual design, said bubble-fountains 11 consisting of a bowl 17, provided in its center with a raised nipple 18 having a channel 18^a and the bowl 17 is further provided with a drainage aperture 19 at one side of said nipple 18. The valve chamber 18^b is cylindrical and one end opens to form an enlarged chamber 18^c which contains the valve-head 22 and valve-head spring 21. Said chamber 18^c carries threads 18^b on its inner periphery for connection with the thread end 18^a 70 of the coupling 13. The valve 20 is of the sliding variety and consists of a valve head 22 in the form of a cylindrical disc, a valve stem 25 consisting of a rod circular in cross section extending from the valve-head 22 75 through the valve chamber 18^b and terminating outside said valve-chamber in the knob 26. The valve-stem 25 is slidably mounted in the opening 25^a of the valve-chamber 18^b and held in proper relation to said opening 80 25^a by the guide 29 diametrically disposed across the central portion of the valve-chamber 18^b and by the threaded plug 28 which has a central bore 28^a through which the valve-stem 25 projects. The plug 28 is further provided at its exterior end with a semi-spherical indentation or socket 28^b in which the knob 26 of the valve-stem 25 seats when the valve 20 is in the open position.

The valve 20 is held normally in the closed position by the action of the helical spring 21 which is contained in the chamber 18^c and seats against the valve-head 22 and the inner end 18^b of the coupling 13. The action of the spring 21 serves to hold the inner face 22^a of the valve-head 22 in the valve chamber 18^b and cuts off the flow of water into the fountain 11. It will readily be seen that a pressure on the knob 26 will force the valve-head 22 back into the chamber 18^c against 100

the action of the spring 21 and allow water from the pipe 8 to flow through the T-joint 10, coupling 13, the now open valve 20 and into the bowl 17 by way of the nipple 18. 5 When the pressure on 26 is released the action of the spring 21 automatically closes the valve 20 and prevents the waste of water. The bowl 17 is drained by the opening 19 which allows the excess water to fall into the 10 drain-trough 14.

The drain-trough 14 is composed of sheet metal or the like and is U-shaped in cross section. The U at the end 14^b is larger than at the opposite end 14^a. This eccentricity of 15 shape causes a slope along the bottom of the trough 14 from 14^a to 14^b and permits rapid drainage of excess water. The spout 15 of the trough is a continuation of the end 14^b and concentrates the flow of excess water into 20 suitable drains (not shown). The trough 14 is carried by the pipe 8 and is attached thereto by two hoops or straps 14^c of strap iron or analogous material suitably fastened to the trough 14 at 14^a and 14^b, respectively, 25 looped over the pipe 8 and fastened thereto by solder or rivets to prevent both lateral or pivotal movement. As the fountains 11 extend forwardly from the pipe 8 it is readily seen that hoops 14^c descend forwardly from 30 the pipe 8 in their loop around the trough 14. Sagging of the trough 14 is prevented by the wires 14^d which encircle the trough 14 and are looped around the outer periphery of the channel 18^a of the fountains 11. 35 It is, of course, understood that this invention can be applied to any water system by merely connecting the pipe 8 to the water supply but its simplicity and obvious low cost make it peculiarly adaptable to the rural 40 communities for use in schools, churches, public halls and the like.

Having thus described my invention, what I claim as new and desire to secure by Letters Patent is:

45 A drinking fountain comprising a jointed horizontally and longitudinally extending fluid supply pipe having a plurality of spaced and aligned fountains mounted laterally thereof, a tapering, semi-cylindrical drain 50 trough arranged below said fountains and having a downwardly curving drain spout at one end thereof, means for suspending said trough from said fountains comprising wires looped around said trough and fountains, and bracing members extending from the ends of the trough to said supply pipe to prevent lateral movement of said trough, each of said fountains comprising a hollow 55 valve casing having inlet and outlet openings and having a valve stem opening, said valve stem opening having an enlarged threaded portion, an enlarged chamber at the inlet end of said valve casing, said chamber 60 having a valve seat formed therein, an up- 65 standing hollow nipple communicating with

said outlet opening of said valve casing, a valve having a stem slidable in said valve stem opening and provided with a spherical knob at one end and with a seat member at the other end thereof to engage said valve seat, a spring disposed in said chamber for normally retaining said valve in closed position, a guide member disposed in said casing intermediate said chamber and said valve stem opening to slidably support said valve stem, said enlarged threaded portion of said valve stem opening having packing for said valve stem arranged therein and a packing nut threadedly received in said threaded portion, and said nut having a semispherical recess formed at the outer end thereof to receive said spherical knob on the outer end of said valve stem when said valve is moved against the tension of said spring into open position.

In testimony whereof I affix my signature.
THOMAS J. SEXTON.
